UNITED STATES PATENT OFFICE

103,715

DESIGN FOR A STOCKING DARNER

William A. Davis, Chicago, Ill.

Application July 31, 1936, Serial No. 64,161

Term of patent 14 years

To all whom it may concern:

Be it known that I, William A. Davis, a citizen of the United States, residing at Chicago, in the county of Cook and State of Illinois, have invented a new, original, and ornamental Design for a Stocking Darner, of which the following is a specification, reference being had to the accompanying drawing forming a part thereof, in which:

Fig. 1 of the drawing is a perspective view of the stocking darner, showing my new design; and Fig. 2, a transverse sectional view in elevation of the article shown in Fig. 1.

I claim:

The ornamental design for a stocking darner, as shown.

WILLIAM A. DAVIS.
